UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN, A CORPORATION

CRANE

Application filed May 17, 1930. Serial No. 453,275.

This invention relates to crane excavators and contemplates the provision of an excavator of this type wherein the hoisting drums are located exterior of the cab or body to permit maximum free range of movement for the cables controlled therefrom while at the same time the bearings and operating mechanism for the drums are fully housed and protected.

10 In crane excavators as heretofore constructed, it has been customary to mount the cable drums inside of the cab body and extend the cables through openings or slots formed in the wall of the body, or else provide hinged covers, trap doors, and other devices to accommodate the cables, which require a wide range of movement during the hoisting and racking-in and crowding-out operations. This construction has always 15 proved objectionable in that the body or cab of the excavator would leak during rainy weather and expose the operator as well as the machinery in the cab to the elements.

In the present invention, the body or cab 20 of the excavator is provided with an open recess or well in which the cable drums are mounted, while the operating mechanism for the drums is housed in the cab, so that the cable has an unlimited range of movement 25 without requiring any openings, doors, or the like to be formed in the cab body.

There is found to be practically no advantage in covering the drum mechanism by which the hoisting and other operations of 30 the excavating device are controlled and effected incident to the action of the dipper shovel, dragline, clamshell and other classes of cable and bucket equipments which are employed in conjunction with excavators of 35 the kind to which this invention relates. Therefore it is desirable for the purpose of saving expense and difficulties incident to building machines, that the drum mechanism be not housed, the exposure of the cable surfaces enabling ready attachment of the cables

and substitution of other cables where necessary, as well as the application of laggings which are often applied to these drum members.

In the drawings—

Figure 1 is a perspective view of a crane excavator embodying the features of the present invention.

Figure 2 is a horizontal sectional view taken on the line 2—2 of Figure 1, and

Figure 3 is a view similar to Figure 2, taken on the line 3—3 of Figure 1.

The numeral 5 generally designates the tractor or crawler structure of the excavator, having a body or cab 6 mounted thereon, said cab being formed with a recess or well 7. The cable drums 8 and 9 for the excavator are disposed in the well 7 and are of usual construction, being provided with supporting shafts 10, drive gearing 11, clutch mechanism 12, operating linkage 13, 13a, 13b, 13c, and control levers 13d. The cab body may be constructed of any suitable material usually sheet metal, and the side flanges 8a and 9a of the drums 8 and 9 are preferably mounted in relatively snug openings formed in the side walls 14 of the well 7 and the shafts 10 for the cable drums project at opposite extremities through the side walls 15a of a supporting housing or casing generally indicated 75 at 15, the walls of which should be of substantial construction in order to provide a support of sufficient strength to withstand the weight of the cable drums 8 and 9. An engine for driving the drums is diagrammatically 80 illustrated in Figure 2 at E.

It will thus be seen that the cable drums are mounted exterior of the cab while the operating parts and controls are under cover and fully housed and protected, and are accessible from the interior of the cab. The cables wound on the drum are thus permitted a free range of movement without forming cable slots, hinge covers, trap doors, and the like in the walls of the cab or body.

It will be apparent from the foregoing that according to the construction of my crane with the cable drums exposed, the latter are readily accessible to the operators of the machine for purposes of changing the cables when necessary, as when a cable is worn out, or a different type of cable and bucket equipment is required to be applied to the machine. Also the drums are so exposed that they may be readily supplied with drum laggings for increasing their diameter, or such laggings may be readily removed, when the matter of changing the cable line oftentimes becomes important to the action of a particular type of excavator equipment to be used for the purposes of the crane operating mechanism.

Having thus described my invention, what I claim as new and desire to secure by Letters Patent of the United States, is—

1. A crane excavator of the type comprising a supporting base, and a cab-like housing carried thereon, operating mechanism within the housing for boom and cable apparatus that may be mounted upon the base, said cab-like housing including a well at the end at which the boom and cable apparatus may be mounted, said well extending vertically through the cab-like housing, together with cable drum mechanism supported in the well and leading to the operating mechanism within the cab-like housing, said cab-like housing containing therein an operating station.

2. In an excavating crane of the type comprising a base, and a cab-like housing supported on the base and containing an operating station, operating machinery within the cab-like housing, said cab-like housing having a vertical well extending therethrough and open at one end of the housing at which boom and cable apparatus are mounted, cable drum mechanism extending across the said vertical well and connected with the operating machinery within the housing, the cab-like housing forming a general enclosure for the operating station and the operating machinery, and the well aforesaid being formed by walls of the housing maintaining the latter a substantially enclosed structure but enabling the drum mechanism in the well to remain exposed.

3. A crane excavator provided with a recessed body closed on all sides and having within it intercommunicating compartments for an operator and operating mechanism, cable drums disposed in said recess and provided with shafts projecting through the walls thereof into the compartments within the said body, and mechanism for driving said drums connected to said shafts interiorly of said body.

4. A crane excavator provided with a body formed with inter-communicating compartments with an open well therebetween, op-

posing compartments being defined by, housings disposed on opposite sides of said well, the said housing defining compartments for an operator and operating mechanism, cable drums mounted in said well and provided with shafts which project at opposite extremities through the walls of said housings into the opposing compartments, and mechanism for operating said drums mounted in said housings and having an operative connection with said shafts.

In testimony whereof I affix my signature.

ERICH H. LICHTENBERG.
